(57) **CLAIM**

We claim, the ornamental design for a connector assembly for a surgical instrument, as shown and described.

DESCRIPTION

FIG. 1 is a top, front, right-side perspective view of a connector assembly for a surgical instrument;

FIG. 2 is top view thereof;

FIG. 3 is a front view thereof;

FIG. 4 is a right-side view thereof;

FIG. 5 is a left-side view thereof;

FIG. 6 is a rear view thereof; and,

FIG. 7 is a bottom view thereof.

The broken lines in the drawings illustrate portions of the connector assembly for a surgical instrument and form no part of the claimed design.
